UNITED STATES PATENT OFFICE.

MICHAEL J. DOUGHERTY, OF CARBONDALE, PA., ASSIGNOR OF ONE-HALF
TO JOHN BURNETT AND EDWARD McHALE, BOTH OF SAME PLACE.

CAR-COUPING.

SPECIFICATION forming part of Letters Patent No. 290,005, dated December 11, 1883.

Application filed October 3, 1883. (No model.)

To all whom it may concern:

Be it known that I, MICHAEL J. DOUGHERTY, of Carbondale, in the county of Lackawanna and State of Pennsylvania, have invented a new and Improved Car-Coupling, 5 of which the following is a full, clear, and exact description.

The invention consists in the combination, with a draw-head, of a pendulous bar pivoted 10 to or suspended from the same, which bar is provided at the lower end, which is within the draw-head, with a weighted lug, and with a projection extending in the direction toward the outer end of the draw-head, which projection holds the coupling-pin raised until the 15 entering link pushes the pendulous bar back and permits the pin to drop through the link.

Reference is to be had to the accompanying drawings, forming part of this specification, in 20 which similar letters of reference indicate corresponding parts in both the figures.

Figure 1 is a longitudinal sectional elevation of two cars coupled by means of my improved car coupler. Fig. 2 is an end elevation of a car 25 provided with my improved coupler.

The draw-head A, which is of the usual construction, is provided in the bottom with a longitudinal slot, A', in front of which the usual pin-apertures are provided. Two blocks, 30 B, project from the end of the car, and on one of them a standard, B', is secured, to which a lever, C, is pivoted, which passes through a longitudinal slot, D', in a standard, D, on the other bumper or block B. An offset or shoulder, E, is formed in one edge of the slot D', on which offset the free end of the lever C can be 35 rested when the said free end of the lever is to be held raised. The lever E extends to the side of the car, or nearly so, and, if desired, can 40 be connected with a rod extending to the top of the car. To the middle of the lever E is pivoted a pendulous locking-bar, F, which is

provided at its lower end with an inwardly and downwardly inclined weighted lug, G, and with a prong, H, projecting toward the 4 outer end of the draw-head. The top of the draw-head is provided with an aperture or opening, A², through which the pendulous bar passes.

The operation is as follows: When a car is 5 uncoupled, the free end of its lever E is raised and held in this position on the shoulder E. As the coupling-pin J rests on the projection H, it will also be raised. The weighted lug G tends to swing the weighted bar F toward the end of the draw-head, thus keeping the projection H in place. If the link K enters, it strikes the bar F below the projection H and swings the bar F inward, thereby moving the projection H from under the pin J, which drops through the link K, thereby coupling the two cars together. If a link is held in one draw-head, and the free end of the said link is to be raised more or less, so that it can pass into the opposite draw-head, which may be higher or lower, the lower weighted end of the pendulum-bar is permitted to act by its own weight on the inner end of the link more or less, in the manner shown in the right-hand side of Fig. 1, by removing the free end of the lever C from the projection E and lowering the lever more or less, as may be required.

Having thus described my invention, what I claim as new, and desire to secure by Letters Patent, is—

In a car-coupling, the combination, with a pin-supporting bar, F, of the lever C and standard D, slotted at D', and having shoulder E, as and for the purpose specified.

MICHAEL J. DOUGHERTY.
